UNITED STATES PATENT OFFICE.

ADOLPH WITT, OF STRASBURG, GERMANY.

RAZOR-STROP.

SPECIFICATION forming part of Letters Patent No. 651,588, dated June 12, 1900.

Application filed July 29, 1899. Serial No. 725,558. (No model.)

To all whom it may concern:

Be it known that I, ADOLPH WITT, cutler and manufacturer of chirurgical instruments, a subject of the German Emperor, residing at 5 Metzgerstrasse 14, Strasburg, Alsace, Germany, have invented certain new and useful Improvements in Razor-Strops; and I do hereby declare the following to be a full, clear, and exact description of the invention, such as will enable others skilled in the art to which it appertains to make and use the same.

The object of my invention is to construct an improved razor - strop which is readily adaptable to razors of various sectional forms and widths and either flat or curved.

In order that my said invention may be particularly described and ascertained, reference is hereby made to the accompanying drawings, in which similar letters of reference indicate corresponding parts.

Figures 1 and 2 are longitudinal sections at right angles to each other, Fig. 2 showing the steel springs and leather band curved.

a designates the outside leather band, the 25 two ends of which are secured to the metallic block *c* by screws.

b b are two plates of spring-steel, which support and distend the leather *a*. The two ends of each of the springs *b* are held by 30 snugs integral with the metallic blocks *c* and *d*, as shown in Fig. 2.

i is a screw-threaded rod integral with the handle *k* and capable of revolving therewith.

35 *l* is a screw the inner end of which enters an annular groove formed in the rod of the screw *i*, whereby the latter is secured in its bearing in the block *c*.

m m are rods made fast to the block *c*, and 40 *n n* are tubes made fast to the block *d*, the said rods sliding telescopically in the tubes, as shown, and operating as guides to the blocks *c* and *d*.

h is a nut to the screw *i*, this nut being soldered to the tubes *n n*.

45 By means of the screw *i* and nut *h* the blocks *c* and *d* can be caused to approach toward or recede from each other, whereby the

curvature of the springs *b* and leather *a* can be regulated as required to suit razors of various sectional forms and widths.

For the purpose of stretching the leather band *a* when it has become slack a set-screw *f*, threaded into a plate *e*, is fitted, the end of the screw abutting against the block *d*, as shown. The plate *e* is fitted with pins *g*, guided in corresponding holes of the block *d*.

The scale shown on one of the rods *m* serves to determine the degree of convexity of the steel blades *b b* and leather *a* to suit the sectional forms and widths of the razors.

Having now particularly described and ascertained the nature of my said invention and in what manner the same is to be performed, I declare that what I claim is—

1. The combination in a razor-strop of the two flexible and convexly-curved plates *b*, wedge-shaped blocks connecting said plates, a flexible covering or surface for sharpening razors, forming a continuous band around said plates, telescoping members connecting said blocks, a nut carried thereby substantially midway of said blocks, and a screw-threaded rod engaging said nut for approaching or receding said blocks toward or from each other, respectively, whereby the convexity of the plates can be regulated, substantially as described.

2. The combination in a razor-strop of the two flexible plates *b* having opposite convex surfaces, the blocks *c d* connecting said plates, flexible coverings or surfaces *a* adapted for sharpening razors, tubes *n n* rigid in the block *d*, and rods *m m* rigid in the block *c* adapted to telescope in said tubes, a nut *h* rigid on said tubes, and a screw-threaded rod *i* engaging said nut for approaching or receding said blocks toward or from each other, respectively, whereby the convexity of the plates can be regulated, substantially as described.

3. The combination in a razor-strop of the two flexible plates *b* having opposite convex surfaces, the blocks *c d* connecting said plates, flexible coverings or surfaces *a* adapted for sharpening razors, tubes *n n* rigid in the block *d*, and rods *m m* rigid in the block *c* adapted

to telescope in said tubes, one of said rods having a graduated scale, a nut *h* rigid on said tubes, a screw-threaded rod *i* engaging said nut for approaching or receding said blocks toward or from each other, respectively, a handle *k* attached to said rod, and of the set-screw *f* and nut *e*, the latter having pins *g* adapted to enter into correspond-

ing recesses in the block *d*, as and for the purpose set forth.

In testimony whereof I affix my signature in presence of two witnesses.

ADOLPH WITT.
